UNITED STATES PATENT OFFICE.

JAMES J. HENNESSY, OF NEW YORK, N. Y.

LUBRICATOR.

Application filed July 27, 1922. Serial No. 578,018.

My invention relates to journal lubricators of the type illustrated in Patent No. 1,378,452, issued to me May 17, 1921, and consists in an improved lubricator especially adapted for use in locomotive lead and trailer trucks.

In the pumping devices of such lubricators it is customary to provide a pumping cylinder having inlet and discharge openings at intervals which necessitates a substantial 10 travel of the pump piston in order to pump any of the lubricant. Repeated reciprocal movement of the piston would not pump any lubricant unless the movement was enough to pass and repass these openings.

One object of my present invention is to provide in a lubricator a pumping arrangement in which any reciprocal movement of the plunger will produce a discharge of the lubricant, thereby rendering the pump much 20 more sensitive than those previously used.

Another object of my invention is to eliminate the necessity of adjusting the pump operating members while the lubricator is installed in the driving box or journal box.

In the above-mentioned patent, the pump is actuated by relative movement of the journal box and the wheel hub. It is not always feasible to obtain the pump movement in this manner and in the present invention the 30 pump operating movement is provided by movement of a lubricator container in the truck box.

In the accompanying drawings which illustrate my invention,—

Figure 1 is a longitudinal section through my improved lubricator and showing a portion of the journal to which it is applied and a member secured to the truck box.

Figure 2 is an end view of a driving box 40 in which my lubricator is positioned and shows the journal in cross section.

Figure 3 is a detail taken on line 3—3 of Figure 1.

Figure 4 is a longitudinal section corresponding to Figure 1 but showing a modified construction in which my improved pumping mechanism is applied to a wheel-operated lubricator.

Figure 5 is a top view of the lubricator 50 shown in Figure 4.

The lubricator comprises a lubricant reservoir 1 in which a waste or other packing container 2 is mounted to slide vertically and is yieldingly supported on a spring 3 55 compressed between the bottom of container 2

and an upwardly facing surface on an up-standing member 4 preferably formed integrally with the lubricator 1. Extending horizontally of member 4 and below the normal surface of the lubricant container in 60 the reservoir is a cylindrical passage 5, one end of which is open and the other end of which terminates in an upwardly-extending passage 6 provided with a ball check valve 7 and leading into the waste container 2. 65

Slidably fitting in passage 5 is a tubular plunger 8, one end of which projects beyond the passage and is slotted longitudinally to receive an upwardly extending bracket 9 clamped upon an operating rod 10 which extends at opposite ends through the side wall of the reservoir and into a recess 11 in member 4. Cotter pins 12 through the plunger 8 on opposite sides of bracket 9 serve to retain the latter in position thereon and a 70 bolt 13 serves to clamp the bracket onto rod 10. The spring 14 compressed between bracket 9 and the opposing face of member 4 tends to thrust the bracket, rod 10, and plunger 8 to the right. A bar 15 extending 80 across the face of the driving box A engages the outer end of rod 10 for the purpose hereinafter mentioned.

The inner end of the plunger is provided with an annular shoulder 16 and a circular disk 17 is slidable in the enlarged portion of the plunger but adapted to contact with the shoulder to form a flop valve. The wall of the plunger is bent over at several places as indicated at 18 to retain disk 17. Disk 90 85 17 is preferably provided with an axial stem 30 which tends to maintain disk 17 in the position shown and renders it more sensitive to opposing movements of the lubricant. With this plunger construction any outward movement of the plunger will permit passage of the corresponding amount of lubricant past disk 17 and any return movement of the plunger will trap this lubricant and force it past ball check 7. 95

The lubricator is shown as assembled with a locomotive driving box by means of pins 19 which extend through the driving box wall and through a slot 20 formed in the side wall of the lubricator or cellar. The bottom of the lubricator is recessed at 21 to accommodate pin 19. The pin and slot retaining arrangement for the lubricator permits movement of the lubricator longitudinally of the 105 driving box and such movement will be 110

induced by the inertia of the box when the wheels mounted upon journal B strike a frog, switch, or a curve in the track. If the thrust is in one direction, the movement will be 5 positively created by engagement of rod 10 and bar 15. If the thrust is in the opposite direction, the movement will be provided by expansion of spring 14.

My lubricator may be applied to the driving box of the locomotive in place of the usual cellar and does not require a special design of box and only slight work to adapt same to operate the lubricating mechanism. It may, therefore, be applied as a substitute 15 for other cellars and at a minimum cost.

In the modification shown in Figures 4 and 5, the pump plunger is operated by contact of rod 22 with the hub 23 of a wheel. The plunger flop valve consists of a ball 24 instead of the disk shown in the preferred 20 construction and the lubricant reservoir or cellar is shown with an extended portion 25 adapted to project beyond the truck box and provided with lugs 26 whereby it may 25 be filled. In this modification the delivery elements are modified by the introduction of a member 27, the mouth of which contacts with journal C. Member 27 is yieldingly supported by coil spring 28 seated on a 30 shoulder formed in the upwardly extending passage 29 leading from the pump cylinder.

Various other modifications of the details of construction of the lubricator may be made without departing from the spirit of 35 my invention as expressed in the appended claims.

I claim:

1. In a journal lubricator, a lubricant reservoir, an upstanding member therein provided with an L-shaped passage having an 40 intake end in the reservoir at the outer end of its horizontal leg, and a delivery end at the upper end of its vertical leg, a hollow reciprocating plunger in the horizontal leg 45 of said passage, and a flop valve in said plunger.

2. In a journal lubricator, a lubricant reservoir, an upstanding member therein provided with an L-shaped passage having an 50 intake end in said reservoir at the outer end of its horizontal leg and a delivery end at the upper end of its vertical leg, a hollow reciprocating plunger extending substantially throughout the horizontal leg of said 55 passage, a valve in said plunger near the inner end thereof, and a check valve in the

vertical leg of said passage near the bottom thereof.

3. In a journal lubricator, a lubricant reservoir, an upstanding member on the bottom 60 thereof provided with a horizontal passage opening at one end into said reservoir and with a discharge passage leading from the other end of said horizontal passage, a hollow plunger reciprocating horizontally in 65 said horizontal passage, and a flop valve in said plunger.

4. In combination, a truck axle box, a lubricant reservoir slidable longitudinally therein, a lubricant pump in said reservoir, 70 and pump operating means adapted to be actuated by horizontal movement of said reservoir in said box.

5. In combination, a locomotive driving box, an oil cellar mounted to slide longitudinally of said box, a pump in said cellar, a pump operating element projecting through the side of said cellar and contacting with 75 said box and actuated by movement of said cellar in said box, and a journal contacting member yieldingly supported in said cellar and receiving lubricant from said pump. 80

6. In combination, a locomotive driving box, an oil reservoir positioned between the sides of said box, a slotted ear thereon extending longitudinally of said box, a pin through the side of said box and said slot for retaining said cellar in said box, and oil pumping means actuated by inertia-induced movement of said cellar in said box provided and limited by the pin and slot cellar retaining arrangement. 90

7. In combination, a locomotive driving box, an oil reservoir mounted to slide longitudinally of said box, an oil pump in said 95 cellar, a pump actuating rod extending through the wall of said cellar longitudinally of said box, an element on said box located to engage the projecting end of said rod, and a spring, compressed between the 100 opposing surfaces on said cellar and said rod, tending to thrust said rod against said element.

8. In combination, a truck axle box, a lubricant reservoir slidable horizontally therein, a lubricant pump, and interengaging elements on said box and reservoir for operating said pump upon relative horizontal movement of said box and reservoir. 105

In testimony whereof I hereunto affix my 110 signature this 18 day of July, 1922.

JAMES J. HENNESSY.
